UNITED STATES PATENT OFFICE.

PETER BUCHHEIT, OF CHICAGO, ILLINOIS.

AUTOMATIC STOP FOR ELEVATORS.

SPECIFICATION forming part of Letters Patent No. 651,339, dated June 12, 1900.

Application filed April 2, 1900. Serial No. 11,118. (No model.)

To all whom it may concern:

Be it known that I, PETER BUCHHEIT, a citizen of the United States, residing at Chicago, in the county of Cook and State of Illinois, have invented certain new and useful Improvements in Automatic Stops for Elevators, of which the following is a specification.

This invention relates to elevators, and has for its object the production of a mechanism, automatically operative, to prevent the fall of an elevator-car when the hoisting-cable breaks from any cause.

In the embodiment herein shown of this invention the hoisting-cable of the elevator passes underneath two sheaves mounted on levers pivoted to the car. The usual guide on each side of the elevator-shaft is provided with teeth adapted to be engaged by dogs pivotally mounted on the elevator. The weight of the elevator-car suspended upon the hoisting-cable, acting through a series of levers, holds said dogs from engaging said teeth. When the hoisting-cable breaks, suitably-arranged weights throw the dogs into engagement with said teeth and prevent the falling of the elevator-car.

In the accompanying drawings, Figure 1 is a front elevation of an elevator-car provided with this automatic stop, portions of the framework of the car being broken away to show the operating mechanism. Fig. 2 is a plan view of the upper beam of the elevator-car, the idler-pulley being removed. Fig. 3 is a side elevation of an elevator-car, showing the stop mechanism, the guide-block E being removed.

Like letters of reference indicate corresponding parts throughout the several views.

In the construction of this elevator I provide the floor A, the side beams A', and the two-part top beam composed of the pieces A² and A³. Midway of the length of said top beam I journal the idler-pulley A⁴ upon the shaft A⁵, passing through the two members A² and A³ of the top beam. Adjusting-bolts A⁶ have a screw-thread engagement with the plates A⁷, extending across the top of said members A² and A³ near the ends thereof.

B represents two levers mounted at their inner ends upon the pivot B'. Each of said levers B is provided with a pair of upwardly-extending ears B², and between each pair of

ears is journaled an idler-sheave B³, under each of which sheaves the hoisting-cable is intended to pass, said cable extending over the idler-pulley A⁴, journaled between said sheaves B³ in the top beam of the elevator-car. At their outer ends said levers B are provided with the recesses B⁴, and in each of said recesses B⁴ the hooked end of one of the vertical bars C is intended to rest. The bars C extend downward outside of said side beams A' of the elevator-car, each dividing in the two-part rods C', the said parts of which rods are connected together by the sleeves C², internally screw-threaded with right and left threads for adjusting the length of the rod C'.

D is a vertical guide for the elevator-car, fixed within the elevator-shaft on each side thereof and extending from the top to the bottom of said shaft. It is provided upon its face with the wedge-shaped projections D', the upper part of which projections constitute teeth D², to be engaged by the stopping-dogs to be later described.

A guide-block E on each side of the elevator is secured to the side beams A' of the car near the lower ends of said side beams, and these guide-blocks are arranged to embrace the vertical guides D. Each of said guide-blocks contains the two dogs E', pivotally mounted therein upon their bearings E² and adapted to engage the teeth D² of the vertical guide D in the elevator-shaft. Said dogs E' have the integral rearwardly-extending weight-levers E³, upon which levers are mounted the slidable weights E⁴, having set-screws E⁵ for securing them in position upon the levers E³. Each of the downwardly-extending rods C' has a pivotal connection by means of the bolt E⁶ with one of the weight-levers E³.

F is the hoisting-cable, extending from the winding-drum (not shown) and passing underneath the two idler-sheaves B³ and over the idler-pulley A⁴ in the top beam of the elevator-car. Both ends of the hoisting-cable may extend to the winding-drum, or one end may be fixed to a stationary support in the upper end of the elevator-shaft and only one end of the cable pass over the winding-drum.

In the normal operation of the mechanism the weight of the elevator-car is carried upon the idler-sheaves B³ and their pivoted supporting-levers B, said weight being practi-

5 eally balanced by an adjustment of the weights E⁴ on the weight-levers E³ of the dogs E'. The height to which said pivoted levers B may be raised is limited by the adjusting-bolts A⁶ in the plates A⁷, and the position of the dogs E' relative to the teeth D² in the vertical guides D is adjusted by the threaded sleeves C² on the two-part rods C'. When the elevator operates normally, the cable F 10 holds the pivoted levers B upward at their outer ends against the adjusting-bolts A⁶, thereby holding the weight-levers E³ elevated and the dogs E' out of engagement with the teeth D² of the vertical guides D. If the cable F becomes slack, as by breaking, the pivoted levers B cease to suspend the weights E⁴, and the latter instantly drop, thrusting the dogs E' into engagement with the teeth D² of the guides D in the elevator-shaft, preventing the car from falling. Springs may be 15 used in the place of the weights E⁴, if preferred.

I claim as my invention—

1. In an elevator, in combination, a top beam; an idler-pulley journaled thereon; two levers pivotally connected to said top beam; 25 a sheave rotatably mounted on each of said levers; two locking-dogs; and means for connecting each of said levers to one of said dogs.
2. In an elevator, in combination, a top beam; an idler-pulley journaled thereon; two levers pivotally connected with said top beam; a sheave rotatably mounted on each of said levers; two pivoted locking-dogs, each having a weight-lever; a weight for each of said 35 weight-levers; and means for connecting each of said first-mentioned levers with one of said locking-dogs.
3. In an elevator, in combination, a top beam; an idler-pulley journaled thereon; two levers pivotally connected with said top beam; 40

a sheave rotatably mounted on each of said levers; two pivoted locking-dogs, each having a weight-lever; a weight for each of said weight-levers; and two bifurcated rods, each having a pivotal engagement with one of said 45 weight-levers, and an engagement with one of said first-mentioned pivoted levers.

4. In an elevator, in combination, a top beam; an idler-pulley journaled thereon; two levers pivotally connected with said top beam; 50 a sheave rotatably mounted on each of said levers; two pivoted locking-dogs at each side of the elevator; a weight-lever formed integral with each of said locking-dogs; a weight for each of said weight-levers; and a bifurcated rod at each side of the elevator, pivotally connected to said weight-levers on the same side of the elevator, and having a hook engagement with the outer end of one of said 55 first-mentioned levers.

5. In an elevator, in combination, a top beam; an idler-pulley journaled thereon; two levers pivotally connected with said top beam; a sheave rotatably mounted on each of said levers; two pivoted locking-dogs at each side 65 of the elevator; a weight-lever integral with each of said locking-dogs; a weight for each of said weight-levers; a bifurcated rod on each side of the elevator, having a pivotal connection with each of the weight-levers on the 70 same side of the elevator, and a hook connection with the outer end of one of said first-mentioned levers; means for adjusting the length of said bifurcated rod; and a bolt for each of said first-mentioned levers, for limiting the movement thereof. 75

PETER BUCHHEIT.
